UNITED STATES PATENT OFFICE

HYMAN CHARNIN, OF BRONX, NEW YORK

DESIGN FOR A BOOTH PARTITION OR SIMILAR ARTICLE

Application filed July 16, 1930. Serial No. 36,367. Term of patent 3½ years.

To all whom it may concern:

Be it known that I, HYMAN CHARNIN, a citizen of the United States, residing at Bronx, in the county of Bronx and State of New York, have invented a new, original, and ornamental Design for Booth Partition or Similar Article, of which the following is a specification, reference being had to the accompanying drawing, forming part thereof.

Fig. 1, is a plan view of a booth partition or similar article showing my new design.

Fig. 2, is a front elevation thereof.

Both sides of the booth partition are of the same design as shown in Fig. 2.

I claim:

The ornamental design for a booth partition or similar article, as shown and described.

HYMAN CHARNIN.
